CLAIM

The ornamental design for a golf club washer, as shown and described.

DESCRIPTION

FIG. 1 is an isometric view of the golf club washer;
FIG. 2 is a reduced view of the golf club washer;
FIG. 3 is a right side view of the golf club washer of FIG. 2;
FIG. 4 is a plan view of the golf club washer of FIG. 2; and,
FIG. 5 is a bottom view of the golf club washer of FIG. 2.
The back view is the same as the front view.
The left side view is the same as the right side view.
